UNITED STATES PATENT OFFICE

104,773

DESIGN FOR A BATTER DISPENSER

Ralph T. Ganary, Collingswood, N. J.

Application February 23, 1937, Serial No. 67,810

Term of patent 14 years

To all whom it may concern:

Be it known that I, Ralph T. Ganary, a citizen of the United States, residing at Collingswood, in the county of Camden and State of New Jersey, have invented a new, original, and ornamental Design for a Batter Dispenser, of which the following is a specification, reference being had to the accompanying drawing, forming part thereof.

In the drawing:

Fig. 1 is a front elevational view of a batter dispenser showing my new design.

Fig. 2 is a top plan view.

Fig. 3 is a bottom plan view.

I claim:

The ornamental design for a batter dispenser as shown.

RALPH T. GANARY.
